[57] CLAIM

The ornamental design for a golf club head, as shown and described.

DESCRIPTION

FIG. 1 is a perspective view of the golf club head showing my new design;

FIG. 2 is a front elevational view thereof;

FIG. 3 is a side elevational view thereof;

FIG. 4 is a side elevational view thereof;

FIG. 5 is a side elevational view taken from the opposite side of FIG. 3;

FIG. 6 is a top plan view thereof;

FIG. 7 is a bottom plan view thereof.

The broken line showing of a fragmented shaft is for illustrative purposes only.

FIG. 1FIG. 2FIG. 3FIG. 4FIG. 5FIG. 6FIG. 7
